INSTRUMENT MOUNTING

Carl A. Boehm, Cincinnati, Ohio, assignor to The
Cincinnati Milling Machine Co., Cincinnati,
Ohio, a corporation of Ohio

Application December 6, 1949, Serial No. 131,408

11 Claims. (Cl. 250—238)

1

This invention relates to improvements in instrument mountings and has particular reference to an improved mounting for a thermopile or like control unit particularly adapted for utilization in connection with heat treating or like machines.

One of the objects of the present invention is the provision of an improved universally adjustable control head for utilization in connection with a heat treating machine.

A further object of the invention is the provision in connection with such a control head of readily adjustable means for determining the effective viewing area.

Additional object of the invention is the provision of an improved instrument supporting head which will provide maximum heat protection to the contained sensitive electrical or other thermopile unit.

The invention also contemplates the provision of a construction which will provide maximum cooling of the entire unit which may be exposed to either the direct or radiant heat developed during the operation of the machine.

More specifically, the invention comprises a compact adjustable instrument supporting structure having a minimum of exposed parts subject to deterioration from heat and flame, and which will adequately provide for operating coupling of cooling, clearing, and electrical control media with the head in a manner to insure efficient operation thereof.

Other objects and advantages of the present invention should be readily apparent by reference to the following specification, considered in conjunction with the accompanying drawings forming a part thereof, and it is to be understood that any modifications may be made in the exact structural details there shown and described, within the scope of the appended claims, without departing from or exceeding the spirit of the invention.

Figure 1 is a fragmentary view of a machine showing the utilization of the invention in connection therewith.

Figure 2 is an enlarged plan view of the instrument head with parts broken away.

Figure 3 is a vertical sectional view on the line 3—3 of Figure 2.

Figure 4 is a vertical section on the line 4—4 of Figure 2.

Figure 5 is a similar section on the line 5—5 of Figure 2.

Figure 6 is a cross section of the supporting arm indicating the relationship of the several conduits as on line 6—6 of Figure 2.

2

Figure 7 is a longitudinal sectional view on the line 7—7 of Figure 6.

Figure 8 is a section on the line 8—8 of Figure 2, and

5 Figure 9 is a transverse section of the lower end of the head in a plane indicated by the section line 9—9 of Figure 5.

The present invention relates to an instrument supporting head particularly designed to effect location of a thermopile or like control unit 10 in proper relationship to a work support, such as 11 of a heat treating machine having a frame designated as an entirety by the numeral 12.

10 The specific detail of the machine forms no part of the present invention, but a characteristic form is illustrated, for example, in copending application of Strauchen et al., Serial No. 755,944 filed June 20, 1947, which is now Patent No. 2,523,883, granted September 26, 1950. As is conventional in machines of this general type, a work piece to be operated on may be mounted on the spindle 11 where it is subject to a suitable heating action performable by controlled flame jets or the like (not shown) directed against the work.

15 It is the purpose of a viewing or controlling instrument to determine the nature of reaction produced on the work, and, if des'red, to effect automatic control of the heating or reacting medium. For this purpose, a suitable sensitive thermopile or similar device 10, which may be in the form of a "rayotube," is employed. This device is located in the socket or mounting 13 and is provided with the electrical terminals as at 14 coupleable through the wires 15 in conduit 16 with a suitable recording or controlling mechanism (not shown).

20 The present invention relates primarily to the means for supporting the control unit in proper proximity to the work piece during heat treating or like operations. For this purpose, there is provided a supporting head having a body portion 17 formed with a recess or seat as at 18 to receive the unit 13 and having depending therefrom the tapering nozzle portion 19 providing the central viewing passage 20. The member 19 terminates in an inturned flange 21 providing the guide rib 22 having seated against one face the target disc 23 formed with the elongate or other desired shape of viewing aperture 24. On the opposite face of the rib a washer 25 secured as by screws 26 to the member 23 rotatably mounts the target disc on the rim, permitting of its angular rotation as desired according to the particular plane or area of the work it is desired to view, while the amount of tightening of screws

26 serves frictionally to vary the ease of rotation of the target or to lock the same in position when greater permanence of location thereof is desired.

The body portion is provided with a flared annular portion 27 constituting the upper part of the head and is additionally provided near its lower end with a peripheral rib or flange 28. This flange, as particularly illustrated in Figure 9, is provided with a notch or aperture at 29 to receive the lower end of the coolant injecting tube 30 which extends through the flange into the space 31. A second notch or aperture 32 formed in the flange 28, and illustrated as located diametrically opposite the point also provides communication between the areas circumscribing the nozzle 19 at opposite sides of flange 28.

An enclosing sheath or sleeve, preferably of brass or other light weight material, which can be readily drawn or formed has a portion as at 35 shaped to closely interfit with and be secured as by brazing or the like to the portion 27 of the body of the head and extends in spaced relation to the nozzle portion 19 to provide the annular coolant chamber 36.

In continuation, it interfits with the flange 28 and is terminally suitably secured to the end of the nozzle portion 19, providing a closure as well for the coolant chamber 31.

For mounting of the unit, the member 17 is provided at one side with the bracket lugs 37 and 38 connected by the pivot 39 with tongue 40 of the end block or bar portion 41 of the overarm 42. This tongue is provided with suitably flattened sides for interfitting engagement with the members 37 and 38.

Adjustably secured to the bed unit 12 of the machine by bolt 43 is a bracket 44 having a furcated portion 45 to which is pivoted sleeve 46 receiving the overarm 42 in a manner to permit of rotative and longitudinal adjustment of the arm. A bolt 47 serves to clamp the overarm in desired adjusted position.

As particularly illustrated in Figures 6 and 7, the overarm includes an inner tube or sleeve 48 telescoping at one end with the block 41 and interfitting at the other with the cap 49.

Surrounding the sleeve at its ends are the spacing rings 50 and 51 which, in turn, support the outer sleeve 52. These parts are preferably secured together as by welding or brazing and provide intermediate the sleeves the coolant receiving space or chamber 53. Extending through the cap 49 at one side is the coolant input pipe 54 threaded as at 55 into the tapered portion of the coolant passage 56 in block 41 and having its opposite end projecting as at 57 to receive the flexible conduit 58 connected with a suitable source of water or other cooling medium by way of elbow 80 and pipe 81.

Threaded into the side of block 41 is the connector nipple 59 from which loops upwardly a flexible conduit 60 connected by nipple 61 to passage 62 in the upper portion of the body member 17. The passage 62 is intermediately blocked as by pipe plug 63 while the bracket lug 38 has the respective transverse passage 64, vertical passage 65, and reversely extending passage 66 formed therein in circumscribing relation to the pivot 39 so that incoming cooling liquid will circulate through the passages, and around the pivot, tending to minimize heating of the lug 38 when the instrument is in use. The passage 62 has a reduced continuation 67 below plug 63 in communication with the passage 66 and has fitted therein the coolant injecting tube 30 which, as previ-

ously pointed out, extends to the space 31 below the rib or flange 28. The injected coolant will therefore flow from the supply pipe through the circumscribing chamber of the overarm 42 and passages or conduits as described to the lower or work approximating portion of the instrument holder, creating liquid pressure at that point.

This introduction of liquid will force the fluid upwardly through notch 32 in the flange and the annular coolant chamber 36 for discharge through passages 68, 69, 70, 71, and 72, nipple 73, and discharge conduit 14.

It will be noted that the passages 68 to 72 inclusive are formed in the member 37 in a manner similar to the passages 62 to 67 in the lug 38, thus circumscribing the pivot 39 and cooling this portion of the mounting at the opposite side. The conduit 74 is connected to nipple 75 carried by the block 41 and the return coolant flow is through passage 76 in the block, the coolant chamber 53 of the overarm, discharge passage 77 and nipple 78 mounted on cap plate 49. Nipple 78 provides the attachment for the second flexible coupling 79 which may return the coolant to a suitable reservoir.

In this manner a free continuous flow of coolant may be effected from supply to exhaust which flows interiorly through the overarm and direct to the area of the instrument support subjected to greatest heat and thence by way of the coolant chambers on the exterior of the instrument support and the overarm to prevent excessive heating of these parts. While it is understood that the members 60 and 74 may occupy different relationships than those shown, it is preferred that they be in the form of arches or loops as shown, permitting various angular adjustments of the support head about the pivot 39 with a minimum of distortion, flexing or displacement of the conduits and at the same time positioning them as remotely as possible from the source of heat when the machine to which the attachment is applied is being utilized for heat treating operations.

For accuracy of operation of the member 13 in checking or control of the functioning of the machine it is necessary that the nozzle portion of the viewing tube be maintained clear of spray, dirt or other foreign substances which might deleteriously effect the accuracy of reading as respects the radiant heat conditions existing at the work.

For accomplishment of this result, utilization is made of a clearing blast of air introducible into the nozzle adjacent the lens or receiving portion 82 of the device 10 through the discharge passage 83. This passage is coupled by a vertical passage 84 formed in the body 17 connected by a cross passage 85 with an additional transverse passage or bore 86 formed in the outer portion of the lug 37 and terminating in the pivot pin receiving aperture 88 thereof. The pin or pivot 39 is formed with the annular connecting groove 89 and is interdrilled to provide a longitudinally extending or axial passage 90 which, in turn, is connected by the cross drilling 91 with a second annular groove 92. This latter groove is so located as to register with passage 93 formed in the block 41 which terminates in a threaded socket to receive one end of the air pipe or tube 94 which in a manner similar to the tube or pipe 54 extends longitudinally through the space contained within the overarm 42 and beyond cap 49 for connection with a suitable source of compressed air (not shown). The member 41 is further provided with an addi-

tional conduit passage 95 correspondingly provided with a tube 96 extending from the member 41 through the cap plate 49 at the upper or outer end of the overarm, and inwardly terminating short of the end of the tongue 40.

As particularly indicated in Figure 2, the wire containing conduit 16 which may be of spun glass or other suitable heat resisting material extends through passage 95 and tube 96 mechanically protected by the passage and overarm as respects tangling or physical injury, and additionally to a maximum feasible degree is insulated against undue heat reaction by the coolant circulation through the adjacent instrument supporting lug and the circumscribing water jacket of the main portion of the overarm.

From the foregoing it will be evident that in utilization of the instrument supporting unit or mounting of the present invention the device as an entirety may be readily located upon the machine in connection with which it is to be utilized and the general angular and in and out position determined by suitable adjustments of the overarm while particular angular relationship of the head itself are correspondingly effected by tilting movement about the pivot 39 while the field of view or reaction area is determined by a rotation or angular adjustment of the target screen.

At the same time the interior of the nozzle or signal receiving portion of the instrument is given maximum cooling effect by a surrounding water circulation jacket and an interior clearing blast and that this is effected substantially in its entirety through contained cooled and protected conduits and passages formed in the supporting arm and instrument head itself without interferences due to various angular adjustments and that a minimum of exposed connections subject to heat or other possible harmful conditions are employed.

It will further be noted that the head of the supporting arm is provided with a kerf or slot 97 aligned with the terminus of the passage 95 and with the aperture or passage 98 in the upper portion of the body 17 of the instrument supporting head. The wire containing conduit 16 extends, as indicated in Figures 2 and 3, through the passage 95 adjacent the pivot 16 to the instrument 18, the kerf providing sufficient space for free swinging of the conduit during pivotal adjustment of the head.

In addition, it will be noted that to assist in protecting the general pivotal connection between the arm and the head itself there has been provided the heat deflecting plate or pan 99 secured as by bolts 100 to the underside of the lugs 37 and 38, thus forming protection to this general area as well as to the upwardly looped conduit elements 60.

What is claimed is:

1. An instrument support of the character described including a head, a supporting arm therefor, said head and said arm having conduit passages formed therein, and a pivot interconnecting said parts, said pivot having axially spaced circumferential grooves respectively aligned with the passage of the arm and the passage in the head and an axially extending passage interconnecting the grooves whereby continuous connection is provided between the passages in the head and arm for any relative angular adjustment of the parts about the pivot.

2. An instrument support of the character described, including a supporting arm having a

head portion and a cap portion, spaced telescoping sleeves including an inner sleeve member interconnecting the head and the cap members, a second sleeve member surrounding the first in spaced relation thereto to provide a chamber, said head having conduit passages formed therein, a first conduit member extending interiorly of the inner sleeve and coupled with one of the passages in the head, a second conduit member coupled with the chamber between the sleeves, the inner sleeve being formed with an orifice providing communication between said chamber and the other of the passages in the head, an instrument supporting head pivoted to the head portion of the supporting arm having a coolant chamber formed therein, and means coupling the passages in the head portion of the arm with the coolant chamber at spaced points to provide circulation of coolant in the chamber by way of said passages.

3. An instrument support of the character described, including a supporting arm having a head portion and a cap portion, spaced telescoping sleeves including an inner sleeve member interconnecting the head and the cap members, a second sleeve member surrounding the first in spaced relation thereto to provide a chamber, said head having conduit passages formed therein, a first conduit member extending interiorly of the inner sleeve and coupled with one of the passages in the head, a second conduit member coupled with the chamber between the sleeves, the inner sleeve being formed with an orifice providing communication between said chamber and the other of the passages in the head, an instrument supporting head pivoted to the head having a coolant chamber formed therein, means coupling the passages in the head with the coolant chamber at spaced points to provide circulation of coolant in the chamber by way of said passage, means dividing the chamber in the instrument head into upper and lower portions, and a conduit member directly connecting one of the passages in the head with the lower portion of the chamber for directly injecting coolant into said lower portion of the chamber.

4. An instrument support of the character described, including a supporting arm having a head portion and a cap portion, spaced telescoping sleeves including an inner sleeve member interconnecting the head and the cap members, a second sleeve member surrounding the first in spaced relation thereto to provide a chamber, said head having conduit passages formed therein, a first conduit member extending interiorly of the inner sleeve and coupled with one of the passages in the head, a second conduit member coupled with the chamber between the sleeves, the inner sleeve being formed with an orifice providing communication between said chamber and the other of the passages in the head, an instrument supporting head pivoted to the head having a coolant chamber formed therein, means coupling the passages in the head with the coolant chamber at spaced points to provide circulation of coolant in the chamber by way of said passage, means dividing the chamber in the instrument head into upper and lower portions, and a conduit member directly connecting one of the passages in the head with the lower portion of the chamber for directly injecting coolant into said lower portion of the chamber, said dividing means having an additional passage formed therethrough providing communication between the

spaced chambers for circulation of coolant therebetween.

5. An instrument mounting including a supporting head having a body portion provided with an interior instrument receiving seat and a communicating viewing tube, said head having a tapered nozzle portion forming the outer wall of the viewing tube, said nozzle being interiorly formed near the terminus thereof with an outwardly extending peripheral rib, a tapered sheath member circumscribing the body portion of the head and extending in spaced surrounding relation to the nozzle portion of the body, said sheath interfitting with the rib on the nozzle and having a portion extending therebeyond in interfitting engagement with the terminus of the nozzle whereby annular coolant chambers are provided intermediate the nozzle portion of the head and the circumscribing sleeve on opposite sides of the rib, said rib having a pair of apertures formed therethrough providing communication between said chambers, a coolant injector tube extending by way of one of the chambers through an aperture in the rib and communicating with the other of the chambers, a first conduit means coupled by way of the head to said tube, and a second conduit means coupled by way of the head to the other chamber whereby continuous coolant circulation may be effected through the respective chambers.

6. An instrument mounting including a supporting head having a body portion provided with an interior instrument receiving seat and a communicating viewing tube, said head having a tapered nozzle portion forming the outer wall of the viewing tube, said nozzle being interiorly formed near the terminus thereof with an outwardly extending peripheral rib, a tapered sheath member circumscribing the body portion of the head and extending in spaced surrounding relation to the nozzle portion of the body, said sheath interfitting with the rib on the nozzle and having a portion extending therebeyond in interfitting engagement with the terminus of the nozzle whereby annular coolant chambers are provided intermediate the nozzle portion of the head and the circumscribing sleeve on opposite sides of the rib, said rib having a pair of apertures formed therethrough providing communication between said chambers, a coolant injector tube extending by way of one of the chambers through an aperture in the rib and communicating with the other of the chambers, a first conduit means coupled by way of the head to said tube, and a second conduit means coupled by way of the head to the other chamber whereby continuous coolant circulation may be effected through the respective chambers, a hollow supporting arm for the instrument head, conduit means extending interiorly of said arm and means coupling the conduits within the arm with the head conduits for circulation of the coolant by way of the arm to the head.

7. An instrument mounting including a supporting head having a body portion provided with an interior instrument receiving seat and a communicating viewing tube, said head having a tapered nozzle portion forming the outer wall of the viewing tube, said nozzle being interiorly formed near the terminus thereof with an outwardly extending peripheral rib, a tapered sheath member circumscribing the body portion of the head and extending in spaced surrounding relation to the nozzle portion of the body, said sheath interfitting with the rib on the nozzle and hav-

ing a portion extending therebeyond in interfitting engagement with the terminus of the nozzle whereby annular coolant chambers are provided intermediate the nozzle portion of the head and the circumscribing sleeve on opposite sides of the rib, said rib having a pair of apertures formed therethrough providing communication between said chambers, a coolant injector tube extending by way of one of the chambers through an aperture in the rib and communicating with the other of the chambers, a first conduit means coupled by way of the head to said tube, and a second conduit means coupled by way of the head to the other chamber whereby continuous coolant circulation may be effected through the respective chambers, a hollow supporting arm for the instrument head, conduit means extending interiorly of said arm and means coupling the conduits within the arm with the head conduits for circulation of the coolant by way of the arm to the head, a pivot interconnecting the head and the arm, means providing an additional conduit within the arm, the head having intercommunicating passages formed therein extending from the pivoted portion thereof to the interior of the nozzle portion of the head, and the pivot having conduit passages formed therein interconnecting said last-mentioned conduit means in the arm and the conduit passages in the head, when the parts are in assembled relation whereby a clearing blast may be directed into the interior of the viewing tube by way of the hollow supporting arm and pivot.

8. An instrument supporting head including a body portion having a pair of supporting lugs, and a nozzle portion providing a viewing tube, a sleeve circumscribing the nozzle portion in spaced relation thereto to provide a coolant chamber therearound, a support for the head, a pivot extending through the lugs and engaging the support for pivotal connection of the parts, each of said lugs having a circuitous passage formed therein extending around the pivot in spaced relation thereto and communicating at one end with the nozzle surrounding chamber, a first conduit coupled with the circuitous passage in one of the lugs for introduction of coolant into the passage and a second conduit coupled with the circuitous passage of the other lug to receive coolant therefrom whereby circulated coolant will be effective as respects both the lugs and coolant chamber of the head to minimize the heating thereof.

9. An instrument supporting head including a body portion having a pair of supporting lugs, and a nozzle portion providing a viewing tube, a sleeve circumscribing the nozzle portion in spaced relation thereto to provide a coolant chamber therearound, a support for the head, a pivot extending through the lugs and engaging the support for pivotal connection of the parts, each of said lugs having a circuitous passage formed therein extending around the pivot in spaced relation thereto and communicating at one end with the nozzle surrounding chamber, a first conduit coupled with the circuitous passage in one of the lugs for introduction of coolant into the passage and a second conduit coupled with the circuitous passage of the other lug to receive coolant therefrom whereby circulated coolant will be effective as respects both the lugs and coolant chamber of the head to minimize the heating thereof, a tubular supporting arm for the head, a jacket surrounding the arm in spaced relation thereto to provide a circumscribing coolant cir-

culation chamber, means coupling one of the conduits from the instrument supporting head with said chamber, independent conduit means extending through the tubular arm, and means connecting the other of the conduit means of the head with said independent conduit means whereby a continuous circulation system circumscribing the supporting arm and the instrument supporting head is provided.

10. An instrument support for protected presentation of a thermopile in cooperative relation to a heated work piece or the like including a supporting head having an instrument receiving seat and a depending nozzle portion adjacent the seat providing a viewing tube, a supporting arm for said head, and a pivot connecting the head to the arm for annular adjustment, said head having spaced walls providing a coolant chamber circumscribing the tube and laterally extending lugs spanning the arm and engaging the pivot, the arm comprising a head portion, a cap, and a sleeve interconnecting said head portion and cap, a plurality of conduit tubes within the sleeve interconnecting the head portion and cap of the arm, a sleeve member circumscribing the first sleeve in spaced relation thereto and providing a circumscribing coolant circulating chamber, said head portion of the arm having a plurality of conduit passages formed therein communicating individually with said conduit means and with said circumscribing chamber, each of the lugs of the instrument supporting head having a circuitous coolant passage formed therein communicating with the circumscribing coolant chamber of the nozzle, looped flexible conduits each connecting a passage in the head with a passage in one of the lugs, the head and one of the lugs having an additional series of passages formed therein interconnecting the lug and the interior of the nozzle, and the head of the supporting arm and the pivot having communicating passages formed therethrough communicating with said additional passages in the instrument supporting head whereby a clearing blast may be connected through one of the contained conduit means in the arm through said passages to the interior of the instrument supporting head.

11. An instrument support for protected presentation of a thermopile in cooperative relation to a heated work piece or the like including a supporting head having an instrument receiving seat and a depending nozzle portion adjacent the seat providing a viewing tube, a supporting arm

for said head, and a pivot connecting the head to the arm for annular adjustment, said head having spaced walls providing a coolant chamber circumscribing the tube and laterally extending lugs spanning the arm and engaging the pivot, the arm comprising a head portion, a cap, and a sleeve interconnecting said head portion and cap, a plurality of conduit tubes within the sleeve interconnecting the head portion and cap of the arm, a sleeve member circumscribing the first sleeve in spaced relation thereto and providing a circumscribing coolant circulating chamber, said head portion of the arm having a plurality of conduit passages formed therein communicating individually with said conduit means and with said circumscribing chamber, each of the lugs of the instrument supporting head having a circuitous coolant passage formed therein communicating with the circumscribing coolant chamber of the nozzle, looped flexible conduits each connecting a passage in the head with a passage in one of the lugs, the head and one of the lugs having an additional series of passages formed therein interconnecting the lug and the interior of the nozzle, and the head of the supporting arm and the pivot having communicating passages formed therethrough communicating with said additional passages in the instrument supporting head whereby a clearing blast may be connected through one of the contained conduit means in the arm through said passages to the interior of the instrument supporting head, said instrument supporting head having a transverse aperture formed in the upper portion thereof adapted to receive an electrical conduit, the head of the supporting arm having a kerf formed therein aligned with one of the passages thereof and in alignment with said passage in the instrument supporting head to permit limited movement of an electrical conduit upon relative angular adjustment of the instrument supporting head and the arm.
